UNITED STATES PATENT OFFICE.

Claes Ryden, of Cranston, Rhode Island, assignor to Universal Winding Company, of Portland, Maine, a corporation of Maine.

VARIABLE-SPEED DEVICE.

1,085,942.

Specification of Letters Patent.

Patented Feb. 3, 1914.

Application filed June 19, 1913. Serial No. 774,649.

To all whom it may concern:

Be it known that I, CLAES RYDEN, a citizen of the United States, residing at Cranston, in the county of Providence and State of Rhode Island, have invented certain new and useful Improvements in Variable-Speed Devices, of which the following is a specification.

My invention relates to variable-speed devices for controlling the rotation of shafts or other machine elements and consists of improvements in the structure and arrangement of the mechanism thereof.

The object of my improvement is to provide a simple and efficient means for starting the rotation of the shaft, spindle or other driven-element at a relatively slow rate of speed; then gradually increasing the speed until the desired maximum is attained; and thereafter continuing the rotation at a fixed or constant rate.

The invention is fully described in the following specification, illustrated by the accompanying drawings, in which like reference characters designate like parts.

In the drawings:—Figure 1 is an end elevation of my new device showing it applied to a rotatable shaft or spindle; Fig. 2 is a side elevation of a portion of the same, looking in the direction indicated by the arrow *y*, Fig. 1; Fig. 3 is a plan view of the main portion of the mechanism with the elements shown partially in section on the line X—X of Fig. 1; Fig. 4 is a detail view of the screw-cone, friction driving-element of the device; Figs. 5, 6 and 7 are detail views of portions of the locking- or detent-mechanism of the device.

My new device may be applied to a variety of purposes, but is particularly adapted for use on winding machines and similar textile apparatus for controlling the rotation of high-speed spindles or other driven-shafts.

I have preferred to here illustrate the improved mechanism as applied to a winding machine and adapted to control the rotation of the winding-spindle. In machines of this character it is very desirable to start the rotation of the spindle at a relatively slow speed in order to avoid straining or breaking the material being wound thereon. This is especially important when fine yarns or delicate threads are being handled, and particularly so when the material is being

unwound from rotating supply-spools, reels or swifts. Obviously, it is of advantage to wind the material at as high a rate of speed as consistent with its strength and the main difficulty hereto experienced has been in starting the rotation of the spindle so as not to impose a too sudden shock or strain on the yarn. In my present improvement I provide means for starting the rotation of the spindle at a comparatively low rate of speed; then, through the action of the automatic controlling-mechanism, the speed is gradually accelerated until the maximum is reached; and thereafter it is maintained uniform until the operation of the spindle is arrested. Through this automatic control I am enabled to provide advantages particularly important as regards the use of the device on textile machinery as above pointed out; but I do not herein limit myself exclusively to such a use as the invention is capable of other applications not herein described.

Referring first to Fig. 2, A designates a portion of the frame of a winding machine which is formed with members *a* and *a'* supporting bearings *b*, *b'* for the rotatable winding-spindle or shaft *B*. Adjacent the bearing *b'*, and in line therewith, is a third bearing *b*² supported in the frame-member *a*² and adapted to receive one end of a driving-shaft *B'*, see Fig. 3, the opposite end-bearing therefor not being here shown. The bearings *b*, *b'*, *b*² are preferably all of the same construction and as here illustrated are of the ball type. Suitable ball-races *b*³ are fitted to the machine-members *a*, *a'*, *a*² and coöperate with the collars *b*⁴ secured on the shafts *B* and *B'* to receive the balls *b*⁵. The balls *b*⁵ run in suitable grooves in the collars *b*⁴ and the ends of the bearings are closed by tight-fitting caps *b*⁶.

Mounted on the driving-shaft *B'* adjacent the bearing *b*² is a belt-pulley *C* secured rotatively therewith by means of the set-screw *c*. The hub *c'* of the pulley *C* is formed at its end with a tapered flange *c*² adapted to serve as a friction driving-means for a disk *D* to be later described. As here shown the pulley *C* has a second flange *c*³ at the opposite end of its hub and this may be used to drive another disk *D* which can be arranged to operate a train of elements similar to those now to be described. In this way the shaft *B'* may be adapted to drive a pair of wind-

ing-spindles arranged in axial alinement therewith, but as the speed-controlling devices would be alike at both ends only one is here shown and described. The shaft B' is 5 turned down at b^7 , where it passes through the bearing b^2 , and mounted on its outer end is a clutch-collar E secured in position by the pin e extending through the shaft. The outer face of the collar E is formed with 10 ratchet-teeth e' adapted to engage with oppositely-formed teeth f on a clutch-member F, see also Fig. 2. The member F is adapted to slide on the end of the spindle or shaft B and is secured rotatively therewith by 15 means of a spline or key f'. The key f' is fastened in the bore of the member F by means of a pin f^2 and slides in a keyway b^8 which extends substantially the whole length of the shaft B. A portion of the key f' is reduced in thickness at f^3 to allow it to project 20 through the bearing b' . The clutch-member F is slid on the shaft B, to engage its teeth f with the teeth e' of the collar E, by means of a sliding element G which is adapted to contact with the end of the key f'. In Fig. 3 25 the member F is shown as withdrawn from engagement with the collar E and a detent-pin f^4 serves to maintain it in its retracted position. The detent-pin f^4 is fitted to slide 30 in a transverse hole b^9 in the shaft B and has its end beveled off to adapt it to engage a slight depression or V-shaped notch f^5 on the under side of the key f'. A spring f^6 in the hole b^9 serves to normally maintain the pin 35 f^4 in engagement with the notch f^5 , but when the member F is moved into engagement with the collar E the pin f^4 is depressed against the action of the spring and then rises to engage a second notch f^7 in the key 40 f'. In this way the detent-pin f^4 acts to engage one or the other of the notches f^5 , f^7 and serves to maintain the clutch-member F against accidental displacement. It will be 45 noted that the member F is formed with a peripheral, tapered flange f^8 which is adapted to be engaged by the beveled end h of a lever H to force the member F away from engagement with the collar E as later explained.

50 The friction-disk D which is driven from the pulley C is mounted on the end of a countershaft I arranged at an angle to the shaft B, in the same axial plane therewith, and adapted to rotate in two bearings j , j' of a swinging bracket J. Referring to Figs. 1 and 2, the bracket J is of rectangular shape with two legs j^2 , j^2 pivoted on a rod j^3 extending horizontally from the side of the main frame A. The disk D is formed with 55 a hub d secured to the shaft I by the pin d' and is provided with screw-threads d^2 on its periphery. The rim of the disk D is beveled off at d^3 to adapt it to engage the outer face of the flange c^2 of the pulley C and a 60 second disk D' arranged parallel with the

main disk has its rim engaging with the inner, beveled face of the flange c^2 . The auxiliary disk D' is mounted loosely on the hub d and is held rotatively with the disk D by means of a stud d^4 projecting from the latter to engage the hole d^5 . Screwed on to the end of the hub d is a collar d^6 between which and the disk D' is a saucer-shaped spring d^7 . The spring d^7 tends to force the disk D' toward the disk D and thereby provides a frictional grip between the rims of the two disks and the sides of the flange c^2 . By adjusting the collar d^6 on the hub d the tension of the spring d^7 can be varied to regulate the pressure of the disks D, D' 80 against the flange c^2 .

Mounted on the shaft I between the bearings j , j' of the bracket J is a friction driving-cone K secured rotatively with the shaft be means of the set-screws k , k extending 85 through its hub k' . Referring particularly to Fig. 4, the periphery of the cone K is scored with relatively deep screw-threads k^2 having a slight pitch or lead from one end to the other. The threads k^2 are left-handed and are adapted to engage with the beveled flange l of a friction-disk L mounted 90 on the member G which takes the form of a sleeve adapted to slide on the spindle B. The sleeve G is formed with a flange or head g at one end against which the disk L is held yieldingly through the action of a spring g' . The spring g' surrounds the sleeve G with one end held by a wire ring g^2 sprung into a groove g^3 , while its opposite end bears against the disk L. The disk L has its bore l' formed slightly convex to provide for a limited rocking movement with respect to its axis, and carries a transverse pin l^2 projecting into an enlarged hole 95 g^4 in the head g of the sleeve G. In this way the disk L is held rotatively with the sleeve G, but at the same time it can be moved slightly out of a right-line position in 100 relation to the axis of the sleeve. The purpose of this arrangement is to provide for a slight floating movement of the disk L on the sleeve G so that it can find its proper relation to the threads k^2 on the cone K when the two are carried 105 into mesh with each other. As before stated, the sleeve G is free to slide on the spindle B, but is held rotatively therewith by a key g^5 engaging the keyway b^8 . Normally, the sleeve G is maintained in the position 110 illustrated by full lines in Fig. 3 by a spring-pressed yoke G', see Fig. 2. The yoke G' is fitted to a groove g^6 on the periphery of the sleeve G, and reaching upwardly therefrom is attached to a sleeve G² mounted to 115 slide on a rod M which extends through the frame-members a, a' and a². Surrounding the rod M is a coiled spring m arranged with one end bearing against the frame-member a' while its opposite end bears 120

against the yoke G. The tendency of the spring m is to slide the yoke G' and sleeve G in the direction indicated by the arrow z, Figs. 2 and 3, and the movement of the sleeve G in this direction is limited by a buffer-spring G³ mounted on the spindle B. Preferably, the spring G³ is of saucer-shape having a central portion g¹ surrounding the spindle B with prongs g⁸ reaching radially outward therefrom to bear against the bearing cap b⁶.

As before explained, the bracket J is mounted free to swing on its bearings on the rod j³ and its position is controlled by means of an upwardly-extending arm N held fast on the rod by a set-screw n. The arm N and bracket J are yieldingly-connected by a spring n' arranged as follows: One end of the spring n' is hooked through a hole n² at the upper end of the arm N and its opposite end is fastened to a stud j⁴ extending through a hub j⁵ on the bracket J. The stud j⁴ has a longitudinal slot j⁶ which is engaged by a pin j⁷ in the hub j⁵, to keep it from turning, while its outer end is threaded to receive a nut j⁸. By turning the nut j⁸ the stud j⁴ can be adjusted longitudinally in the hub j⁵ to vary the tension of the spring n'. Below the spring n' a pin n³ reaches laterally outward from the arm N to receive a second coiled spring n⁴ which bears against a boss j⁹ on the bracket J. The spring n⁴ is slightly stronger than the spring n' and serves to hold the arm N and bracket J the proper distance apart. Secured to the rod j³ by a set-screw n⁶ is a horizontally-extending operating-handle N' through which the rod j³ and arm N are rocked manually for a purpose as later explained. At the top of the arm N is a detent-catch which serves to hold the arm in the position illustrated in Fig. 1 to cause the spring n' to maintain the friction-disks D, D' in engagement with the flange c². Normally, the action of gravity tends to swing the bracket J outward to carry the disks D, D' away from the pulley-flange c², and a stop-pin a⁷ projecting from the side of the frame A is adapted to limit the movement of the bracket in this direction.

The detent-catch or lock for the arm N consists of a three-armed lever O pivoted on a rod o secured in the hub a³ of the frame A and extending horizontally therefrom, see Figs. 1, 2 and 5. One arm o' of the lever O extends across the upper end of the arm N, as shown by dotted lines in Fig. 1, and is formed with a shoulder o² adapted to engage with the edge thereof. Referring to Fig. 2, a coiled spring o³ surrounds the rod o with one of its ends engaging a hole o⁴ in the lever O while its opposite end is held by a collar o⁵ secured to the rod by the set-screw o⁶. The tendency of the spring o³ is to hold the lever O locked in engagement

with the arm N as illustrated in Figs. 1 and 5. Another arm o⁷ of the lever O extends upwardly and carries at its end a knock-off device P, shown more particularly in Figs. 3 and 5. This consists of a stud p formed at its end with a forked head p' in which is mounted a wheel or disk p² pivoted on the pin p³. The threaded end of the stud p extends through a hub o⁸ at the end of the arm o⁷ and is formed with a longitudinal groove p⁴ which is engaged by a pin p⁵, see Fig. 5, to keep the stud from turning in the hub. Two nuts p⁶, p⁸ are screwed onto the stud p and set up against the opposite ends of the hub o⁸ to hold the stud in position. By adjusting the nuts p⁶ on the stud p its position in the hub o⁸ can be changed to regulate the relation of the wheel p² to the spindle B, see Fig. 3. It will be noted that the periphery of the disk p² is beveled off on one side which adapts it to be engaged by the beveled face g⁹ of the head g on the sleeve G. This engagement occurs when the sleeve G has been slid along the spindle B to the position illustrated by dash lines in Fig. 3 through the action of the friction-cone K as more fully described hereinafter. The effect of this engagement is to force the knock-off device P away from the spindle B and this action rocks the lever O against the tension of its spring o³ to release the detent-arm o' from the end of the arm N.

As before stated, the rod o is held fast in its bearing in the frame A and a lever R is mounted free to turn on the rod adjacent the hub of the lever O. Referring to Fig. 6, the lever R is formed with a laterally-extending arm r terminating in a hub r' in which is secured a rod S by means of a set-screw s. The rod S is also held in a similar hub h' supported on an arm h² reaching out from the hub h³ of the lever H, see Fig. 7. Through this means the rod S is adapted to swing bodily about the axis of the rod o in the direction indicated by the arrow 2, Fig. 1. The movement of the rod S in this direction is limited by a lug a⁴ projecting from the side of the frame A, with which it is adapted to contact, see Fig. 1. The lever R is formed with a depending arm r² formed at its end with a hub r³ through which a screw r⁴ projects. The end of the screw r⁴ is preferably rounded off at r⁵ and is adapted to be engaged by a lug n⁵ on the arm N, see Figs. 1 and 2. The screw r⁴ is adjustable in the arm r² and is held in position by a check-nut r⁶. The engagement of the lug n⁵ with the screw r⁴ provides for moving the lever R from the movement of the arm N when the latter is rocked by the handle N'. Projecting laterally from the arm r² above the hub r³ is a lug r⁷ carrying an adjustable screw r⁸ secured in position by the check-nut r⁹. The rounded end of the screw r⁸ is adapted to engage the lower end 130

of a downwardly-projecting arm o^9 formed as a part of the lever O. The purpose of this arrangement is to provide for rocking the 5 detent-lever O to release the arm N when the rod S is moved downward as above described.

Mounted on the rod S outside of the lever R is a detent-arm T which is secured in position by a set-screw t extending through 10 its hub t' , see Figs. 1, 2 and 6. The upper end of the arm T is formed with a shoulder t^2 adapted to engage a corresponding shoulder u on the end of a curved lever U. The lever U is mounted free to turn on the rod 15 M at the top of the frame A and is controlled by a spring u' coiled around the rod. One end of the spring u' engages a hole u^2 in the hub of the lever U and the opposite end is held in a hole o^3 in the cross-bar o^6 of the 20 frame A. Referring to Fig. 6, the tendency of the spring u' is to rock the lever U to swing its lower end against the end of the detent-arm T. The arm T and lever U are here shown with their detent-shoulders t^2 and u in engagement, and when the 25 shoulders are released the curved face u^3 at the end of the lever U will ride across the end of the arm T during the movement of the lever U under action of the spring u' . 30 The movement of the arm T is limited by the rod S striking the lug a^4 so that the end of the lever U is not allowed to slide off from the end of the arm T.

Having now described the construction 35 and arrangement of my new device in detail, its method of operation will be next explained:—Referring first to Fig. 1, when it is desired to start the rotation of the shaft or spindle B the handle N' is moved upwardly in the direction indicated by the arrow 3. This action serves to rock the rod j^3 to swing the arm N against the end of the screw r^4 on the lever R, and the latter is rocked thereby to move the rod S upwardly 40 in the direction opposite to that indicated by the arrow 2, Fig. 1. This upward movement of the rod S carries the arm T into position for its detent-shoulder t^2 to be engaged by the shoulder u on the lever U and 45 this engagement is effected through the action of the spring u' . The movement of the rod S also acts to swing the clutch-lever H away from the flange j^8 on the clutch-member F so that the latter is free to be 50 moved into engagement with the clutch-collar E as later described. In the meantime, the upper end of the arm N will have been moved past the shoulder o^2 on the detent-lever O, and the spring o^3 will then 55 cause the arm o' to be rocked downwardly, so that when the handle N' is released, the arm N will be held in the position illustrated in Fig. 1. As the arm N is being operated as above described the spring n' which con-

nects it with the bracket J will act to swing 65 the latter in the same direction. This movement of the bracket J brings the friction-disks D, D' into contact with the flange c^2 on the pulley C and also carries the driving-cone K into engagement with the friction-disk L on the sleeve G, and these contacts 70 are then maintained under tension of the spring n' . It will be understood that the pulley C is rotated continuously by means of the usual driving-belt, and when the 75 disks D are engaged with its flange c^2 rotation is imparted thereby to the countershaft I. The shaft I rotates the friction-cone K and through the engagement of the latter with the disk L the sleeve G is turned to rotate the spindle B to which it is keyed. It 80 will be noted that the diameter of the disks D is considerably greater than that of the flange c^2 on the pulley C and therefore the countershaft I is rotated at a much slower 85 rate of speed than that of the pulley. It is also called to attention that the diameter of the cone K at its smaller end, where it first makes engagement with the friction-disk L, is considerably less than the diameter 90 of the flange l . It will therefore be appreciated that as the spindle B first starts to rotate its speed will be much less than that of the pulley C on account of this system of gearing, operating through the countershaft I. In other words, the rotation of 95 the spindle B will be started at a much slower rate of speed than that of the pulley C and shaft B'. It is obvious, also, that this 100 ratio of speed between the shafts B and B' can be varied to suit requirements by altering the relative diameters of the various friction-elements just noted. Furthermore, any other form of driving-element might be employed in place of the pulley C such, for 105 instance, as a gear-wheel.

Immediately the spindle B starts to rotate its speed begins to be accelerated until finally it reaches the speed of the shaft B'. This acceleration is caused by the traveling 110 movement of the disk L along the surface of the cone K due to the pitch or lead of the threads k^2 with which it engages. The ratio between the diameter of the larger or base end of the cone K and the diameter of 115 the disk L is the same as that between the disks D, D' and flange c^2 . Therefore, when the disk L reaches the base of the cone K, as shown by dash lines in Fig. 3, the two 120 shafts B, B' will be rotating at substantially the same speed. At this point the sleeve G, which slides with the disk L on the spindle B, strikes against the end of the key f' in the clutch-member F and forces the latter into engagement with the clutch-member E on the shaft B'. The engagement of the teeth e' on the member E with the teeth f on the member F will then cause 125

the two shafts B and B' to be coupled together so that the spindle B is rotated positively from the shaft B'. At this juncture the beveled face g^o on the head g of the 5 sleeve G comes into contact with the beveled periphery of the wheel p^o of the knock-off device P. This engagement serves to rock the lever O to raise its detent-arm o' from the arm N and the force of gravity will then 10 act to swing the bracket J outward to carry the disks D, D' away from the pulley-flange c^o . This outward movement of the bracket J, which is limited by the stop-pin a^o , also carries the friction-cone K away from the 15 disk L and the spring m acting on the yoke G' then slides the sleeve G back into its normal position, as illustrated by full lines in Fig. 3. The speed-controlling elements are now in their initial positions with the disks 20 D, D' released from engagement with the driving-pulley C and therefore the counter-shaft will remain at rest until the spindle B is started again in the manner above described. The spindle B is now coupled positively 25 with the shaft B' so as to be driven at the maximum rate of speed as imparted through the driving-element or pulley C.

To arrest the rotation of the shaft or spindle B it is only necessary to rock the rod S 30 with respect to the rod o in the direction indicated by the arrow 2, Fig. 1. A very slight movement of the rod o as just described will act to release the detent-shoulders on the arm T and lever U and the 35 spring u' will then act through the lever U to press the arm T farther outward. This movement of the arm T is continued until the clutch-lever H engages the beveled flange f^o on the member F and slides the 40 latter on the spindle B to withdraw it from engagement with the clutch-collar E on the shaft B', as shown in Fig. 2. The movement of the rod S may be accomplished manually or through the operation of suitable 45 knock-off devices, not here shown or described, but well known from their use on winding and like machines.

Should the operation of the stopping-mechanism take place immediately after the 50 shaft B is started and while the counter-shaft I is being driven from the pulley C the disks D, D' will be thrown out of engagement with the pulley automatically as now described: The movement of the rod S 55 downward to release the detents on the arm T and lever U serves to rock the lever R to bring its screw r^o into contact with the lower end of the arm o^o on the lever O. This engagement serves to rock the lever O to raise 60 its detent-arm o' from the end of the arm N and the latter is thereby released to allow the frame J to swing outward from the frame A. This movement of the frame J carries the disks D, D' away from the pul-

ley-flange c^o and also releases the driving-cone K from the friction-disk L, as before described, and in this way the parts are returned to their initial positions again so as to be in place to start the spindle B in the manner as before described. 65

It will be seen that my invention provides a very simple yet efficient means for starting the rotation of the shaft or spindle inductively at a relatively slow speed, and for accelerating this speed until the maximum 70 is reached, whereafter the driving connections are made positive. In this way the rotation of the shaft can be brought gradually up to the maximum without imposing shock or strain on the material being operated upon and the operating parts themselves are also saved from undue strain and wear. It is also pointed out that the device is entirely automatic and so arranged that the starting-devices, that is the friction driving-connections, are only in operation during the time required to start the shaft. As soon as the shaft is driven positively these elements are disconnected and remain at rest until the shaft is again started so that they 75 are not subjected to any unnecessary wear. 80

Various modifications might be made in the form and arrangement of the parts of my new device and in the manner of their application without departing from the spirit or 85 scope of the invention.

Therefore, without limiting myself to the exact construction shown and described, what I claim is:—

1. In a variable-speed device, the combination with a rotatable friction-cone formed with peripheral threads leading from one end to the other, of a disk arranged to contact with the surface of the cone to rotate therewith and adapted to engage the threads 100 on the cone to cause a relative axial movement between the two members. 105

2. In a variable-speed device, the combination with a rotatable driving-cone formed with threads leading from one end to the other of its peripheral surface, of a friction-disk engaging said threads to feed it longitudinally with respect to the cone during its rotation thereby in the manner and for the purpose described. 110

3. In a variable-speed device, the combination with a friction-cone formed with V-shaped threads leading from one end to the other on its periphery, and a friction-disk formed with a tapered, peripheral flange 120 adapted to be engaged by the threads on the cone to cause a relative axial advance between the cone and disk during their rotation one from the other. 115

4. In a variable-speed device, the combination with two shafts, of a friction-cone mounted on one of the shafts and formed with external screw-threads leading from 125

one end to the other, and a disk mounted on the other shaft and adapted to be driven from the cone and to engage the threads thereof to cause it to travel longitudinally 5 of the axis of the latter.

5. In a variable-speed device, the combination with a spindle, of a friction-disk keyed to said spindle and adapted to slide longitudinally thereof, and a friction-cone 10 formed with peripheral threads leading from one end to the other and adapted to engage with the disk to cause the latter to travel longitudinally of the axis of the cone while being driven therefrom.

15 6. In a variable-speed device, the combination with a driving-element, of a countershaft adapted to be driven therefrom, a friction-cone mounted on the countershaft and formed with peripheral threads leading 20 from one end to the other, a spindle arranged opposite the countershaft, and a friction-disk keyed to said spindle and adapted to be engaged by the cone to drive the spindle as it feeds from one end to the 25 other of the cone while traveling in the threads.

7. In a variable-speed device, the combination with a spindle, of a friction-disk secured rotatively therewith, a friction-cone 30 formed with peripheral threads leading from one end to the other, and manually-operable means for causing contact between said cone and disk whereby one is rotated from the other with the threads on the cone 35 engaging the periphery of the disk to cause an axial advance between the two.

8. In a variable-speed device, the combination with a rotatable friction-disk formed with a tapered periphery, of a rotatable friction-cone formed with tapered peripheral 40 threads leading from one end to the other, and means to engage the threads on the cone with the periphery of the disk to cause rotation between the two members and an axial advance of one member with respect to the other.

9. In a variable-speed device, the combination with a driving- and a driven-shaft, of a friction-disk secured rotatively with one 50 of said shafts, a friction-cone secured rotatively with the other shaft and formed with screw-threads on its periphery, and means to adjust the shafts laterally in relation to each other to engage the threads on the 55 cone with the periphery of the disk to cause the rotation of one shaft from the other at a constantly varying speed.

10. In a variable-speed device, the combination with a driving-shaft, of a friction-cone secured rotatively with said shaft and formed with screw-threads on its periphery, a driven-shaft, a friction-disk secured rotatively with said driven-shaft and slidably longitudinally thereof, means to adjust said 60 shafts in lateral relation to engage the disk

with the threads on the cone, and detent-means to maintain the cone in engagement with the disk to rotate the latter and cause an axial displacement therebetween to vary the speed of the driven-shaft.

11. In a variable-speed device, the combination with a shaft mounted to rotate in fixed bearings, of a friction-disk on said shaft, a countershaft, a movable bracket having bearings for the countershaft, a friction-cone on said countershaft formed with peripheral screw-threads, means to move the bracket to engage the threads of the cone with the periphery of the disk, and detent-means to maintain the bracket in position with the cone and disk in engagement. 70 75 80

12. In a variable-speed device, the combination with a shaft rotatable in fixed bearings, of a friction disk on said shaft, a countershaft arranged opposite said fixed shaft, a pivoted bracket supporting the countershaft to move laterally in relation to the fixed shaft, a friction-cone on the countershaft formed with screw-threads adapted to engage the periphery of the friction-disk, a pivoted arm, a spring connecting the arm with the bracket, and means to swing the arm to bring the cone into yielding contact with the friction-disk. 85 90 95

13. In a variable-speed device, the combination with a shaft mounted in fixed bearings, of a friction-disk on said shaft, a countershaft, a friction-cone on the countershaft formed with screw-threads adapted to engage the periphery of the disk, a bracket supporting the countershaft and normally maintained in position by gravity to hold the cone away from the disk, and means to move the bracket to carry the cone into engagement with the disk. 100 105 110

14. In a variable-speed device, the combination with a shaft mounted in fixed bearings, of a friction-disk on said shaft, a countershaft, a friction-cone on the countershaft formed with screw-threads adapted to engage the periphery of the disk, a bracket supporting the countershaft and normally maintained in position to hold the cone away from the disk, an arm mounted opposite the bracket, a spring connecting the arm with the bracket, means to move the arm to operate the bracket to carry the cone into engagement with the disk, and detent-means to lock the arm in position to hold the bracket with the cone and disk engaged. 115 120 125

15. In a variable-speed device, the combination with a rotatable friction-cone having peripheral screw threads, of a rotatable friction-disk adapted to engage said threads to cause a relative axial advance between the cone and disk to vary their ratio of speed, means to engage the cone and disk, and automatically-operated means to release them from engagement after the disk has traversed the length of the cone. 130

16. In a variable-speed device, the combination with a rotatable friction-cone having peripheral screw-threads, of a friction-disk adapted to engage said screw-threads to feed it along the cone during its rotation therefrom, means to maintain the cone and disk in engagement, and means to release them from engagement when the disk feeds to the end of the cone.
17. In a variable-speed device, the combination with a rotatable friction-cone formed with peripheral screw-threads, of a friction-disk adapted to engage the threads on the cone to be rotated thereby and to be fed axially along its surface from one end to the other, means to cause the cone to engage with the disk, detent-means to maintain said engaging-means operative, and means to release the detent-means when the disk has been fed from end to end of the cone.
18. In a variable-speed device, the combination with a rotatable friction-cone having peripheral screw-threads, of a rotatable friction-disk adapted to engage said threads to cause a relative axial advance between the cone and disk to vary their ratio of speed, means to engage the cone and disk, detent-means to hold them in engagement, and means operated automatically to release the detent-means when the disk reaches the end of the cone.
19. In a variable-speed device, the combination with a rotatable friction-cone formed with peripheral screw-threads, of a rotatable friction-disk adapted to engage the threads on the cone to cause a relative axial movement between the two, means to engage the disk and cone, means to release them from engagement, and means to return them to their initial positions after their disengagement.
20. In a variable-speed device, the combination with a rotatable friction-cone having peripheral screw-threads, of a rotatable friction-disk adapted to engage the periphery of the cone to be fed longitudinally thereon, means to engage the cone and disk, means to release them from engagement, and a spring to return the disk to its initial position after being released from the cone.
21. In a variable-speed device, the combination with a rotatable friction-cone formed with peripheral screw-threads, of a rotatable friction-disk adapted to engage the threads on the cone to be fed longitudinally thereof, means to engage the cone and disk, and means operated by the disk at one end of its traverse to release it from engagement with the cone.
22. In a variable-speed device, the combination with a rotatable friction-cone formed with peripheral screw-threads, of a rotatable friction-disk adapted to engage the cone to be fed along its periphery, means to engage

the cone and disk, means operated by the disk at one end of its traverse on the cone to release it from engagement therewith, and means to return the disk to its initial position after its release from the cone.

23. In a variable-speed device, the combination with a shaft, of a sleeve keyed rotatively with said shaft and slidable longitudinally thereof, a friction-disk mounted on the sleeve and formed with a tapered, peripheral flange, a friction-cone formed with peripheral threads adapted to engage with the flange on the disk to travel the latter on the cone, means to carry the cone into and out of engagement with the disk, and a spring to slide the sleeve on the shaft to return the disk to its initial position after it is disengaged from the cone.

24. In a variable-speed device, the combination with a shaft, of a sleeve held rotatively on the shaft and slidable longitudinally thereof, said sleeve formed with an enlarged head at one end, a friction-cone formed with peripheral screw-threads, a friction-disk mounted on the sleeve to engage the threads on the cone and formed with a convex bearing to allow it to rock with respect to the axis of the sleeve, a spring tending to hold the disk against the head on the sleeve, and means to secure the disk rotatively with the sleeve.

25. In a variable-speed device, the combination with a driving-element, of a spindle adapted to be driven therefrom, clutch-devices for connecting the spindle rotatively with the driving-element, a friction-cone adapted to be driven from the driving-element, a friction-disk on the spindle arranged to engage the cone to be driven therefrom and to be traversed longitudinally thereof, and means operated by said disk to render the clutch-devices operative after the disk has traversed the length of the cone.

26. In a variable-speed device, the combination with a driving-element, of a spindle adapted to be driven therefrom, clutch-devices for connecting the spindle rotatively with the driving-element, a friction-cone, means to rotate the cone from the driving-element, a friction-disk on the spindle adapted to be driven from the cone and to be traversed longitudinally thereof, means actuated by the disk to render the clutch-devices operative after the disk has traversed the length of the cone, and means to disengage the cone from the disk after the clutch-devices are in operation.

27. In a variable-speed device, the combination with a driving-element, of a spindle adapted to be driven therefrom, clutch-devices for connecting the spindle rotatively with the driving-element, a friction-cone, means to rotate the cone from the driving-element, a friction-disk on the spindle adapted to be driven from the cone and to be trav-

ersed longitudinally thereof, means operated by the disk to operate the clutch-devices after the disk has been traversed the length of the cone, means to disengage the cone 5 from the disk after the clutch-devices are in operation, and means to return the disk to its initial position after the cone is disengaged therefrom.

28. In a variable-speed device, the combination with a constantly-rotating driving-element, of a clutch-member connected to rotate therewith, a spindle, a clutch-member on the spindle adapted to engage the clutch-member connected with the driving-element, 10 a countershaft adapted to be rotated from the driving-element, a friction-cone formed with peripheral threads mounted on the countershaft, a friction-disk held rotatively with the spindle and adapted to engage the 15 threads on the cone to be fed longitudinally thereof during its rotation therefrom, and means to effect the engagement of the two clutch-members after the disk has traversed the 20 length of the cone.

29. In a variable-speed device, the combination with a driving-element, of a spindle adapted to be driven therefrom, clutch-devices for connecting the spindle rotatively with the driving-element, a friction-cone 30 adapted to be driven from said driving-element, a friction-disk on a spindle arranged to engage the cone to be driven therefrom and to be traversed longitudinally thereof, means to engage the cone and disk, detent- 35 means to maintain them in engagement, means actuated by the disk to operate the clutch-devices after the disk has traversed the length of the cone, and means actuated by the disk to release the detent-means after 40 the clutch-devices are in operation.

30. In a variable-speed device, the combination with a friction-disk, of a friction-cone adapted to engage the disk to rotate the latter and to cause it to be traversed on 45 the surface of the cone, a bracket supporting said cone to carry it into engagement with the disk, a detent-lever to maintain the bracket in position with the cone engaging the disk, and means operated by the disk at 50 the end of its traverse on the cone to actuate the detent-lever to release the cone from engagement with the disk.

31. In a variable-speed device, the combination with a spindle, of a sleeve keyed to 55 the spindle to slide longitudinally thereof, a

friction-disk mounted on the sleeve to rotate the spindle, a friction-cone adapted to engage the disk to rotate the sleeve and cause it to slide on the spindle, means for carrying said cone into engagement with the disk, 60 a detent-lever for maintaining said engaging-means operative, and a wheel on said lever adapted to be engaged by the sleeve to move the lever to release the engaging-means.

32. In a variable-speed device, the combination with two shafts arranged in axial alinement, of a clutch-member on one of the shafts, a second clutch-member slideable on the other shaft to engage the first clutch-member, a friction-cone formed with peripheral screw-threads, a disk on one of the shafts adapted to engage the threads on the cone to be rotated thereby and to traverse the face of the cone, and means operated by said disk to slide the movable clutch-member into engagement with the other clutch-member after it has been traversed the length of the cone.

33. In a variable-speed device, the combination with a driving-element formed with a friction driving-flange, a countershaft, friction-disks on the countershaft adapted to engage the flange on the driving-member, a friction-cone on the countershaft formed 85 with the peripheral screw-threads, and a friction-disk adapted to engage the threads on the cone to be rotated thereby while traversing the surface of the cone.

34. In a variable-speed device, the combination with a rotatable driving-element having a beveled flange, a countershaft arranged at an angle to the axis of the driving-element, a disk on said countershaft adapted to engage one side of the flange on the driving-element, a second disk on the countershaft adapted to engage the opposite side of the flange, means to press the disks together to impinge upon the flange, a friction-cone on the countershaft formed with screw threads, 100 and a friction-disk engaging the cone to be driven thereby while traversing the threads on the cone.

In testimony whereof I affix my signature in presence of two witnesses.

CLAES RYDEN.
